UNITED STATES PATENT OFFICE

168,681

INFANT'S CRIB

Abraham G. Feldman, Chicago, Ill.

Application July 18, 1952, Serial No. 20,680

Term of patent 7 years

(Cl. D5—5)

To all whom it may concern:

Be it known that I, Abraham G. Feldman, a citizen of the United States, and a resident of the city of Chicago, county of Cook, State of Illinois, have invented a new, original, and ornamental Design for an Infant's Crib, of which the following is a specification, reference being had to the accompanying drawing, forming a part thereof, in which:

Figure 1 is a perspective view of an infant's crib, showing my new design.

Figure 2 is an elevational view of a fragment of the side panel shown in Figure 1.

The characteristic feature of the design resides in the appearance of the outside of the side panel,

shown in full lines, the inside of the panel, including the area adjacent the spheres, being plain and unornamented.

I claim:

The ornamental design for an infant's crib, substantially as shown and described.

ABRAHAM G. FELDMAN.
